COLLAR SHAPING MEANS

Max M. Newman, New York, N. Y.

Application December 22, 1945, Serial No. 636,918

9 Claims. (Cl. 2—132)

1

This invention relates to shirt collars and more particularly to shaping means for the collar edge so as to prevent wrinkling and provide a neat appearance thereof.

The failure of many prior devices was attributable to the stiffened, unnatural appearance accorded the collar edge and in general these devices were not adapted to suitable shaping of the collar. In cases where a stiffener element extended the complete length of the collar, that is, from its neck-line to its tip, the rigidity accorded the collar edge prevented it from adapting itself to a tie knot, where a tie was worn with the shirt. As a result, the stiffener element jutted from the shirt front because it was so lifted by the tie knot. Similarly, any movement of the stiffener element in the tie knot region was transmitted in an amplified manner to the remainder of the stiffener element. On the other hand, when the stiffener element was confined to the region below that of the knot, not only was the top or neck-line portion of the collar deprived of any shaping means, but the lack thereof was apparent in an objectionable manner. Thus, when the shirt with the stiffener element incorporated therein was ironed after washing, the end of the element adjacent the knot region was accentuated and presented an apparent line of demarcation in the collar edge. This was, moreover, a most probable source of damage to the collar since the sharp end of the stiffener element was obviously forced into the cloth during such pressing and concentrated the wear at that point. In fact, even in the absence of ironing, the sharp edge of the stiffener element was often noticeable as it presented a resting point for dust or dirt during the wearing of the shirt.

Bearing the foregoing in mind, it is an object of the present invention to provide a collar shaping means which eliminates the above objections while treating the collar edge from the neck-line to the tip.

Another object of this invention is to provide a collar shaping means of a unitary nature wherein movements thereof in the tie knot region of the collar are substantially isolated from the remainder of the shaping means.

A further object of this invention is to provide a collar shaping means which will adapt itself to the complete aesthetic requirements of the collar and will permit the collar to be draped over the tie knot while maintaining suitable rigidity otherwise.

Another object of this invention is to provide a collar shaping means having incorporated

2

therein a semi-flexible member so as to provide shaping without undue rigidity. Allied with this object is the provision of such a semi-flexible member wherein kinking thereof is rendered highly improbable or completely eliminated.

Still another object of this invention is to provide a collar stiffening element which shall avoid damage to either the collar itself or the shirt front in that its sharp edges are prevented from making contact with either of these shirt portions.

Other objects of my invention will be apparent from the following description, it being understood that the above general statements of the objects of my invention are intended to describe and not to limit it in any manner.

In the drawing,

Fig. 1 is a perspective view, partly broken away, of a collar and tie assembly, the collar being provided with the shaping means of the instant invention.

Fig. 2 is an elevational view of the shaping element per se.

Fig. 3 is a greatly enlarged fragmentary view of the flexible portion of the shaping element.

Referring now to Fig. 1, the collar C indicated is of the well known turned-down type provided with the conventional "French" seams at its edges. The shaping element 10 is incorporated between the plies of the collar at the edges 11 and 12 thereof. It will be apparent that the seams 13 and 14 in conjunction with the "French" seams provide a channel into which the shaping element 10 may be inserted. Such insertion may be effected in the manufacture of the collar so that the element 10 is permanently incorporated in said channel or an opening may be provided in the rear side of the collar adjacent the neck-line whereby the element 10 can be inserted or removed, as desired.

The shaping element 10, although unitary in nature, is preferably constructed of three sections of mutually varying degrees of flexibility and elongation and longitudinally continuous in that they are aligned and extend substantially in the same direction. Section 15 thereof is of the greatest rigidity and is proportioned and disposed so as to occupy the central portion of the collar edge. Section 16 is of a relatively flexible nature and is proportioned and disposed so as to control the top or neck-line portion of the collar edge. Section 17 is of the same flexibility as section 16 and is adapted to form the tip region end of the shaping element 10. All of the sections are elongated in that their lengths are ap-

preciable greater than their widths and the sections are end-to-end connected so as to maintain and further such elongation.

Shaping element 10 may comprise an elongated integral strip of metal chain which may take the form of a non-rustable chain having individual links and often used for connection to watches or keys. Assuming purely for the sake of illustration that the length thereof is $2\frac{3}{4}$ inches to accommodate a collar edge of that length, the central portion 15 may be $1\frac{3}{4}$ inches, the top portion 16 may be $\frac{3}{4}$ inch, while the tip portion 17 may be $\frac{1}{4}$ inch. The chain is rendered suitably rigid at the central portion 15 by welding or soldering of its links, although it will be apparent that the section 15 may be solid, if desired, since the soldering or welding of the links produces the same effect. At the portions 16 and 17, the chain links retain their original degree of flexibility or semi-rigidity as is characteristic of such watch chains, such chain of semi-rigidity being less flexible, of course, than the collar edge itself.

Referring to Fig. 3 wherein is shown an enlarged fragmentary view of the flexible portion of the chain, adjacent links, such as 18 and 19, are preferably, although not necessarily, overlapping, as shown. The purpose of such overlapping construction is to prevent kinking of the chain when the shirt is laundered or ironed with the shaping element therein. The degree of overlapping is such as to maintain the adjacent links in their overlapping relationship even under the influence of a sharp bend in the chain. In this way, subsequent ironing of the collar restores the links to their original, substantially parallel relationship in the overlapping portions. The position of the links 18 and 19 is of course identical with all the link positions throughout the flexible portions of the shaping element 10.

The upwardly disposed links 19 are thicker at portion 20, slanting at line 21 so as to fit under the next link 19 as well as under its associated lower link 18. Similarly, link 18 slants downwardly at 22. Each link 18, for example, goes under two other links 18 as well as one 19 so as to increase the overlapping characteristics of the chain. However, it will be appreciated that such construction is optional and not mandatory for the benefits of the invention.

When the shaping element 10 is applied to the channel formed as aforesaid and illustrated in the broken away portion of Fig. 1, the section 16 of the shaping element by virtue of its degree of flexibility effectively drapes itself around the convex top of knot K. The central, rigid section 15 follows thereafter so as to provide the central portion of the edge with a suitable stiffening means. The section 17 follows the rigid section 15 so as to avoid a sharp or penetrating tip on the collar edge.

It will be observed that section 16 assumes an arcuate form while section 15 depends therefrom at an angle. In this manner, the central portion of the collar edge is downwardly directed instead of jutting out in a highly objectionable fashion. Similarly, movements of the top portion 16 are substantially isolated from rigid section 15. This is of advantage inasmuch as section 16 might otherwise act as the short arm of a lever wherein a movement thereof might cause the section 15 to cock upwardly to an amplified degree. Section 17 being of a flexible nature, minimizes wear upon a shirt front such as would be produced by a sharp-edged stiffener

element. Sections 16 and 17 further preserve the surface continuity of the rigid section 15 so as to avoid abrupt lines of demarcation in the collar edge. Such continuity is achieved through 5 the mutually continuous surface alignment of the sections, the expression "mutually continuous surface alignment" being intended to denote that the corresponding surfaces of the several sections lie in the same plane. It will be evident 10 that the alignment of such surfaces prevents marks appearing on the collar edge at the junction of two sections. Such marks would generally be created during ironing of the collar where one section would take up the weight of 15 the iron were the sections not aligned as described.

Chain section 16, while flexible, is nevertheless sufficiently shape-retaining to resist wrinkling of itself or of the collar at its top edge. Chain 20 section 17 similarly renders wrinkling of the tip edge extremely unlikely by virtue of the limited flexibility of the chain.

As is characteristic of such chains as described, they are of sufficient flexibility as to be bendable 25 of their own weight. In this way, the chain may drape itself in the shape illustrated in Fig. 1 without tending to lift the remainder of the collar edge.

I have shown a preferred embodiment of my 30 invention but it is obvious that numerous changes and omissions may be made without departing from its spirit.

I claim:

35 1. Collar shaping means comprising a unitary strip including a flexible chain section and a rigid section depending therefrom, said flexible chain section comprising a lesser portion of said strip than the rigid section whereby said shaping means may be applied to a collar edge wherein 40 said flexible section may drape itself over a tie knot adjacent said collar edge and the rigid section may stiffen the following part of said collar edge.

45 2. A collar stiffening element comprising a unitary strip including a rigid section and a smaller flexible section, said sections being connected, said flexible section being formed with inter-connecting links, adjacent links thereof being overlapping.

50 3. A collar shaping means comprising a rigid elongated section and relatively flexible sections on each end thereof, each of said flexible sections comprising chain members having overlapping links extending over at least two succeeding links.

55 4. Collar shaping means comprising a rigid elongated section and relatively flexible sections at each end thereof, one of said flexible sections being longer than the other, and said rigid section being the longest of the three, each of said flexible sections comprising chain members having overlapping links.

60 5. Collar shaping means for application to a collar edge, said collar shaping means comprising a flexible strip member and a rigid strip member, both said members forming a continuous, elongated strip, said members being substantially aligned and arranged so that the flexible member is disposed above said rigid member when the collar shaping means is applied to said collar edge, said rigid member being longer than said flexible member whereby a large portion of said collar edge is accorded stiffened 65 characteristics while a succeeding, aligned and

smaller portion thereof is accorded less stiffened characteristics.

6. Collar shaping means for application to a collar edge, and means comprising a rigid elongated section and relatively flexible sections connected at each end thereof so as to form a continuous, unitary structure, one of said flexible sections being longer than the other, and said rigid section being the longest of the three whereby the application of said means to a collar edge provides continuous portions thereof with mutually varied degrees of flexibility.

7. Collar shaping means for application to a flexible collar edge, said collar shaping means including an elongated means of individual metallic link construction, said links being mutually bendable and adapted to render less flexible said collar edge to which the elongated means is applied.

8. Collar shaping means for application to a flexible collar edge, said collar shaping means including an elongated means of individual metallic link construction, said links being mutually bendable and adapted to render less flexible said collar edge to which the elongated means is applied, some of the links of said elongated means overlapping at least two following links thereof.

9. Collar shaping means for application to a collar edge, said collar shaping means compris-

ing a unitary strip having at least two elongated sections of different degrees of rigidity, said sections being end-to-end connected to form a continuous elongated strip and being in mutually continuous surface alignment, one of said sections being flexible and adapted to be disposed in the tie knot region of a collar edge and the other of said sections being rigid and depending therefrom so as to provide stiffening means for the 10 succeeding portion of the collar edge.
